SHOE BUFFING MACHINE

Fred Ricks and Charles Turner Jones, Leicester, England, assignors to United Shoe Machinery Corporation, Paterson, N. J., a corporation of New Jersey

Application June 6, 1933, Serial No. 674,565
In Great Britain June 30, 1932

5 Claims. (Cl. 51—273)

This invention relates to shoe buffing machines, and is herein illustrated as disclosed in a buffing machine of the type illustrated and described in the application for United States Letters Patent Serial No. 652,967, filed January 23, 1933, in the name of Fred Ricks, which machine is equipped with a pair of bottom scouring rolls, a small frusto-conical buffering tool for operating upon the breast surfaces of Louis heels and a buffering tool of the disk or Naumkeag type for operating upon the shank portion of shoes.

It is an object of the present invention to provide an improved arrangement for removing dust which results from the operation of buffering tools. In accordance with this object, a feature of the invention consists in the provision, in combination with a buffering roll, of an air blast nozzle beyond and adjacent to one end of the roll arranged to direct the blast of air along the length of the roll, and a suction hood adjacent to the opposite end of the roll for receiving the dust-laden blast of air. In the illustrated machine, the air blast nozzle is positioned adjacent to the free end of the frusto-conical tool referred to, and a treadle-operated mechanism is provided for swinging the nozzle to an out-of-the-way position when the operator desires to replace the abrasive covering of the tool.

The illustrated machine is provided also with a vacuum cleaning brush for removing from the shoes the dust which adheres to them as a result of the buffering operation. This brush is disclosed and claimed in our application for United States Letters Patent Serial No. 679,666, filed July 10, 1933, which constitutes a division of the present application.

These and other features of the invention, comprising various combinations and arrangements of parts, will be best understood from the following description of the preferred embodiment thereof, selected for purposes of illustration and shown in the accompanying drawings, in which

Fig. 1 is a view in front elevation of the improved machine;

Fig. 2 is a longitudinal plan view of a frusto-conical buffering tool having dust-removing devices associated therewith;

Fig. 3 is a sectional view taken on the line III—III of Fig. 2;

Fig. 4 is a plan view of a Naumkeag type of tool in combination with a dust hood; and

Fig. 5 is a side elevation of the tool and hood shown in Fig. 4 with the lower portion of the hood open to render the tool accessible.

The supporting structure of the machine (Fig. 1) consists of a frame 10 in the lower portion of which are mounted bearings 12 for a shaft 14 carrying a pair of fixed and loose pulleys 16 and 18, respectively. A belt shifter having an operating lever 20 is provided for stopping or starting rotation of the shaft 14. Journaled in the upper portion of the frame 10 is a shaft 22 which is driven from the shaft 14 by a belt 24 passing over suitable pulleys upon respective shafts. A shaft 26 is journaled in bearings 28 which also are secured in the upper portion of the frame 10. Mounted upon the shaft 26 are fine and coarse bottom scouring rolls 30 and 32, respectively. The shaft 26 is driven from the shaft 22 by a belt 34. It is the usual practice to reciprocate as well as rotate the shaft which carries bottom scouring rolls and a portion of a reciprocating mechanism is enclosed within a housing 36. Such reciprocating mechanism is fully disclosed in the above-mentioned application Serial No. 652,967, and no further description of it need be given in the present application. Surrounding the upper and rear portions of the bottom scouring rolls 30 and 32 is a dust hood 38 and beneath the bottom scouring rolls is a large dust collecting pan 40. The dust hoods 38 are connected through a branched duct 42 to the intake side of an exhaust blower 44 which is supported in the frame 10 and is driven by a shaft 46. The blower 44 has an outlet opening 45 adapted for connection with a suitable exhaust conduit. Power is transmitted from the shaft 14 to the shaft 46 by a belt 48. A suction pipe 50 connects the lower portion of the pan 40 to the duct 42.

Secured in the upper portion of the frame 10 are a pair of bearings 52 and 54, respectively. A shaft 56, which is journaled in these bearings, carries upon one of its ends a frusto-conical buffering tool 58 provided with a burled nut 59 for securing an abrasive sleeve upon the tool. The shaft 56 extends forwardly and toward the left-hand end of the machine and the tool 58 is mounted upon the forward and left-hand end of the shaft 56, being positioned to the left of the bottom scouring roll 30 and somewhat above the level of the bottom scouring rolls. The shaft 56 would appear, in a plan view, to make an angle of about thirty-eight degrees with a line extending forwardly and rearwardly of the machine; and in a side elevation it would appear to slope downwardly toward its forward end at an angle of about thirteen degrees with the horizontal. Upon its rear and right-hand end the shaft 56 carries a pulley 60. Secured upon the

shaft 22 is a pulley 62 and a belt 64 running over the pulleys 62 and 60 drives the shaft 56. Frusto-conical tools such as the tool 58 are useful in buffing the breast surfaces of Louis heels. For 5 receiving the dust which arises from this operation, there is provided a dust hood 66 (Figs. 1, 2 and 3) of frusto-conical form, the large open end of the hood 66 being adjacent to the end of the tool 58 which is secured upon the shaft 56 10 and the small end of the hood 66 surrounding the shaft 56. The hood 66 is supported by a bracket 68 which is secured upon the upper portion of the bearing 54. A draft duct 70, one end of which is connected to the intake side of the blower 44, 15 communicates with the interior of the dust hood 66 through an opening 72 formed in the wall of the dust hood. In order to distribute the suction, a sector-shaped baffle plate 74 is positioned between the opening 72 and the large open end 20 of the dust hood. The baffle plate 74 is secured to the inner wall of the dust hood 66 and it extends substantially to the shaft 56 with allowance for clearance. Adjacent to the free end of the tool 58 and directed substantially axially with 25 respect to the tool is the open end of an air blast nozzle 76. The air blast nozzle 76 constitutes the discharge end of a conduit 77 having two elbows 79. The intake end of the conduit 77 is mounted for rotation about its axis within a suction pipe 78 which is connected to the outlet end 30 of a blower 80 mounted upon the frame 10. The use of an independent blower such as the blower 80 avoids the necessity of any filtering arrangement which would be required if the pressure 35 were to be taken from the outlet side of the blower 44. The blower 80 has a rotor shaft 82 which is driven from the shaft 14 by a belt 84 passed over suitable pulleys upon the respective shafts. A bracket 86 secured to the upper portion 40 of the frame 10 supports the upper portion of the pipe 78. Secured upon the conduit 77 is a pulley 88 over which runs a chain 90. The pulley 88 is formed for non-slipping engagement with links in the chain 90. The upper end of the 45 chain 90 is connected to a spring 92 which is anchored in an extension of the upper portion of the frame 10. The lower portion of the chain 90 is connected to a treadle 94. When the operator wishes to renew the abrasive cover upon 50 the tool 58 he depresses the treadle 94 thereby swinging the nozzle 76 out of its operative position, as shown in Fig. 1, to an out-of-the-way position. It is sometimes advantageous also to swing the nozzle out of the way to facilitate 55 manipulation of a shoe, especially when the tip end of the tool 58 is being employed for particularly delicate work.

Journaled in bearings supported by a bracket 122 (Fig. 1) is a spindle 124 upon the lower end 60 of which is mounted a buffering tool 126 of the Naumkeag disk type such as is commonly employed in operating upon shanks. A tool of this type is disclosed in United States Letters Patent No. 1,227,622, granted May 29, 1917, upon the application of Ernest Hope. Communicating with a suction conduit 128 supported upon the frame 10 is a dust hood 130 (Figs. 1, 4 and 5) which 65 partially covers the rear face of the tool 126 and which is recessed as indicated at 132 to avoid the spindle 124. The dust hood 130 has a bulged surface 134 to provide an air passage between the hood and the tool. Pivotally connected to the hood 130 by a hinge 136 is an extension 138. The extension 138 partially surrounds the periphery 70 of the tool 126 and has a bottom wall 140 which

is cut away as indicated at 142 in Fig. 4 to expose the working surface of the tool to the work. The extension 138 is normally secured in its upward or operative position, as shown in Fig. 1, by means of a latch 144 which is hinged to the extension at 145 and which engages the upper surface of the hood 130. When it is desired to replace the abrasive cover upon the tool 126 the extension 140 may readily be unlatched and dropped to the position indicated in Fig. 5, thus 10 rendering the tool 126 accessible to a device for applying an abrasive cover. The hood 130 has a flanged portion 146 which is secured by bolts 148 to a bracket 150 which is mounted upon the upper portion of the frame 10. The bracket 122 15 is integral with the hood 130 and extends from the upper surface of the rear portion of the hood. The flange 146 is provided with arcuate slots for the bolts 148 to enable the operator to vary the orientation of the tool spindle 124. The conduit 128 extends up to the flange 146 where it communicates with the interior of the hood 130. The lower end of the conduit 128 opens into the suction duct 42. The spindle 124 carries a pulley 152 which is driven by a belt 154 passing over a 20 pulley 156 on the shaft 22. The belt 154 is guided in its passage to and from the pulley 152 by a 25 pair of idler pulleys (not shown).

For removing the fine deposit of dust which, in spite of the high efficiency of the above described dust-removing devices, may still adhere to the surface of a shoe after the various buffering operations have been performed upon the shoe, there is provided a vacuum cleaning brush 106 (Fig. 1) which is disclosed in detail and claimed 30 in our above-mentioned co-pending application Serial No. 679,666. This brush is mounted upon a suction tube 98 which is secured to the left-hand end of the pan 40 and connected by a pipe 100 to the suction duct 70.

Where, as in the case of the machine disclosed in the above-mentioned application, Serial No. 652,967, the upper portion of the machine frame upon which the various tools are mounted consists of a bracket pivotally mounted for up and down adjustment about the shaft 22, the various draft conduits may be provided with flexible elements to accommodate such adjustment.

Having described our invention, what we claim to be new and desire to secure by Letters Patent 50 of the United States is:

1. A shoe buffering machine comprising a buffering roll, an air blast nozzle beyond and adjacent to one end of said roll arranged to direct a blast of air along the length of the roll, and a suction hood adjacent to the opposite end of said roll for receiving the dust-laden blast of air.

2. A shoe buffering machine comprising a driven buffering roll, means for supporting said roll at one end, the opposite end of said roll being free, an air blast nozzle beyond and adjacent to the free end of said roll arranged to direct a blast of air substantially axially along the length of said roll, and a suction hood adjacent to the supported end of said roll for receiving the dust-laden blast of air.

3. A shoe buffering machine comprising a buffering tool, and a conduit mounted for rotation about its axis and adapted for connection to a supply of air under pressure, said conduit terminating in an air blast nozzle offset from the axis of the conduit, whereby the position of the air blast nozzle relatively to the buffering tool may be varied by rotating the conduit.

4. A shoe buffering machine comprising a buffering

tool, an air blast nozzle normally adjacent to said tool for directing a blast of air toward the tool to remove dust arising from the work, a support for said nozzle constructed and arranged to enable said nozzle to be moved away from said buffering tool, means for maintaining said nozzle in its normal position adjacent to the tool, and treadle-operated means for moving the nozzle from said normal position to render the buffering tool accessible for replacement of an abrasive cover thereupon.

5. A shoe buffering machine comprising a rotary spindle, an elongated buffering tool secured at one

end upon said spindle and having its opposite end free, a frusto-conical dust hood surrounding said spindle and having its large end adjacent to the secured end of said buffering tool and open to receive dust arising from the operation of the tool upon the work, a suction duct opening into the wall of said dust hood, and a sector-shaped baffle plate positioned between said suction duct and the large open end of said dust hood and extending from the inner wall of the dust hood substantially to said spindle.
